UNITED STATES PATENT OFFICE.

HENRY BROOKS, OF WEST MEDFORD, AND WILLIAM E. REED, OF BOSTON,
MASSACHUSETTS.

WOOD-EXHIBITING CARD.

SPECIFICATION forming part of Letters Patent No. 299,052, dated May 20, 1884.

Application filed October 12, 1883. (No model.)

To all whom it may concern:

Be it known that we, HENRY BROOKS, of West Medford, county of Middlesex, and WILLIAM E. REED, of Boston, county of Suffolk, State of Massachusetts, have invented an Improvement in Wood-Exhibiting Cards, of which the following description, in connection with the accompanying drawings, is a specification, like letters on the drawings representing like parts.

This invention relates to exhibiting or show cards adapted to be put up in book form or otherwise, as may be desired, and designed to hold wood or other veneers, said veneers being protected or covered with a glazed covering.

The object of our invention is to permit veneers to be examined as to grain or fiber, to prevent warping thereof, and to cover and protect the veneers from dust, moisture, &c.

To these ends our invention consists in the wood-exhibiting card or device hereinafter particularly set forth and claimed.

In the accompanying drawings, Figure 1 is a plan view of our improved card partially broken out, and Fig. 2 is a cross-section thereof enlarged as to thickness.

Referring to the drawings, A marks the card, having openings of any suitable size and configuration, in which are held the veneers B, of the same or different wood, and cut with or across the grain, so that by means of our invention those interested in the study of wood may see and examine the grain of any variety of wood. These veneers are covered and protected by a glazed substance, C, such as isinglass, gelatine, or glass; but we prefer to use a

transparent covering of mica, because of its greater flexibility and capability of resisting both heat and cold and moisture. Besides permitting an examination of the grain and fiber of the veneers, the covering referred to prevents warping thereof, and protects said veneers from dust, moisture, &c. The covering substance C will preferably be so applied as to serve to hold the veneers in place. It will also be noticed that the veneers are kept smooth and flat when so retained in the cards, and by holding the card between the light and the eye the character of the grain of the wood can be observed and studied or compared or contrasted with the grain of other veneers.

We are aware that it is not new to glue or otherwise secure wood veneers to cards for the purpose of examination and exhibition, and we do not lay any claim thereto.

We claim—

A wood-exhibiting card having an opening therethrough, in which is held a veneer of wood covered on both sides by a glazed covering, whereby the wood is protected, and the grain of the wood can be examined when held between the light and the eye, substantially as set forth.

In testimony whereof we have signed our names to this specification in the presence of two subscribing witnesses.

HENRY BROOKS.
WM. E. REED.
